UNITED STATES PATENT OFFICE

130,205

DESIGN FOR A SHOE BOW OR SIMILAR ARTICLE

Herbert G. Whitehouse, East Orange, N. J.

Application September 26, 1941, Serial No. 103,530

Term of patent 3½ years

To all whom it may concern:

Be it known that I, Herbert G. Whitehouse, a citizen of the United States of America, residing in East Orange, county of Essex, and State of New Jersey, have invented a new, original, and ornamental Design for a Shoe Bow or Similar Article, of which the following is a specification, reference being had to the accompanying drawing, forming part thereof.

Fig. 1 is a front view of a shoe bow or similar article showing my new design.

Fig. 2 is a rear view thereof.

I claim:

The ornamental design for a shoe bow or similar article, substantially as shown.

HERBERT G. WHITEHOUSE.
